UNITED STATES PATENT OFFICE.

THOMAS LUMSDEN, OF GATESHEAD, ENGLAND.

VERTICAL DRILLING AND BORING MACHINE.

1,413,174.

Specification of Letters Patent. Patented Apr. 18, 1922.

Application filed May 20, 1920. Serial No. 382,720.

To all whom it may concern:

Be it known that I, THOMAS LUMSDEN, a subject of the King of Great Britain and Ireland, residing at Gateshead, in the county 5 of Durham, England, have invented new and useful Improvements in Vertical Drilling and Boring Machines, of which the following is a specification.

This invention relates to vertical drilling 10 and boring machines of the type provided with two co-axial tool spindles arranged the one within the other, said spindles being either simultaneously or independently driven, and has for its object to provide an 15 improved construction.

In a machine in accordance with this invention the outer tool spindle is provided with a detachable tool-receiving nose at one end, and with a ball or roller bearing where- 20 by the inner spindle is supported.

I will fully describe my invention with reference to the accompanying drawing which is a part sectional elevation of a vertical drilling machine embodying one construction in accordance with my invention. 25

Referring to the drawings, the outer spindle 1 is made hollow and is provided at its lower end with a detachable nose 2 adapted to receive a drill. Within the outer spindle 30 is disposed an inner spindle 3 also adapted at its lower end to receive a drill. The nose 2 may be connected to the outer spindle 1 by a bayonet joint, by a thread, or by any other device permitting it to be readily attached thereto and detached therefrom. The outer spindle is driven from the driving shaft 4 by bevel wheels 5, 6, through a driving sleeve 7 integral with the bevel wheel 6 provided with a key 8 engaging a 40 long key-way 9 in the outer spindle. The bevel wheel 6 is supported by a bracket 21 on the frame 22 of the machine. The inner spindle 3 is driven through a belt pulley 10 keyed to a sleeve 23 provided with a key 45 11 engaging a long keyway 12 in the upper portion of the inner spindle which projects beyond the end of the outer spindle. The sleeve 23 of the pulley 10 is supported by a ball bearing 24 carried by the head 25 of the 50 frame 22 of the machine. The lower end of the inner spindle 3 is supported by a ball bearing 13 carried by the outer spindle 1, said ball bearing preventing endwise move-

ment of the inner spindle in respect of the outer spindle. 55

The feed in the construction illustrated is common to both spindles, and is operated by a pinion 14 on a shaft 15 carried by the bracket 21 and provided with a hand wheel 16, said pinion engaging a rack 17 attached to a collar 18 bearing against ball thrust 60 bearings 19, 20 on the outer spindle 1. If desired, the feed shaft 15 may be power driven. If desired, I may substitute roller 65 bearings for the ball bearings 13, 19, 20, 24. 65

It will now be seen that the drilling machine herein described has two co-axial tool spindles either of which may be put into operation independently of the other. The outer spindle is intended for use with drills 70 of large diameter, while the inner spindle can be used for drills of small diameter.

If desired, the tool spindles 1 and 3 may be adapted to receive a boring or similar tool 75 instead of a drill.

What I claim as my invention, and desire to secure by Letters Patent is:—

1. In vertical drilling and boring machines, the combination of a hollow outer spindle, a detachable tool-receiving nose secured on 80 said spindle and forming extension thereof, a ball bearing carried by said hollow outer spindle, a tool-receiving spindle within said hollow outer spindle, said inner spindle being supported by said ball bearing, whereby relative endwise movement of said spindles is prevented, bearings for said spindles, means for rotating said spindles, and means for feeding said spindles. 85

2. In vertical drilling and boring machines, the combination of a hollow outer spindle, a detachable tool-receiving nose secured on said spindle and forming an extension thereof, a ball bearing carried by said hollow outer spindle, a tool-receiving spindle within said hollow outer spindle, said inner spindle being supported by said ball bearing, whereby relative endwise movement of said spindle is prevented, bearings for 90 said spindles, means for rotating said outer spindle, independent means for rotating said inner spindle, and means for simultaneously feeding both spindles. 95

In testimony whereof I have signed my name to this specification.

THOMAS LUMSDEN,
